UNITED STATES PATENT OFFICE.

QUADARIO DE SANTIS, OF TRENTON, NEW JERSEY.

DESIGN FOR A DISPLAY-RACK.

49,328.

Specification for Design.

Patented July 11, 1916.

Application filed May 22, 1916. Serial No. 99,246. Term of patent 7 years.

● *To all whom it may concern:*

Be it known that I, QUADARIO DE SANTIS, a subject of Italy, residing at Trenton, in the county of Mercer and State of New Jersey, have invented a new, original, and ornamental Design for Display-Racks, of which the following is a specification, reference being had to the accompanying drawing, forming a part thereof.

Figure 1 is a perspective view looking to-

ward the front of a display rack, showing my new design. Fig. 2 is a similar view looking toward the rear of said display rack.

I claim:

The ornamental design for a display rack as shown.

QUADARIO DE SANTIS.
